APPARATUS FOR MAKING ELECTRON EMITTING MEANS

Filed Jan. 5, 1922

Inventor:
Erwin R. Stoeckle

by C. G. Sprague, Atty.

UNITED STATES PATENT OFFICE.

ERWIN RUDOLPH STOEKLE, OF MILWAUKEE, WISCONSIN, ASSIGNOR TO WESTERN ELECTRIC COMPANY, INCORPORATED, OF NEW YORK, N. Y., A CORPORATION OF NEW YORK.

APPARATUS FOR MAKING ELECTRON-EMITTING MEANS.

Application filed January 5, 1922. Serial No. 527,178.

This invention relates to the manufacture of electron-emitting elements, such as electrodes for discharge devices.

The electron emissivity of substances such as platinum is greatly increased when coated with alkaline earth metal oxides, such as barium, strontium and calcium oxide.

It is the object of this invention to provide a simple and efficient apparatus for and 10 method of applying such a coating to an electrode element; for example, a filament. This object is accomplished by supporting the filament to be coated and a supply of the coating material within a vessel which is 15 preferably evacuated and heating the coating material to cause it to be deposited upon the filament.

This invention will be better understood by having reference to the following specification and accompanying drawing, wherein 20 the apparatus is disclosed.

A glass tube 1 is provided with a neck 2, by means of which it may be attached to a 25 vacuum pump (not shown). In one wall of the tube are sealed the lead wires 3 and 4, to the lower ends of which is attached the filament 5 to be coated. The outer ends of the 30 lead wires 3 and 4 are connected to the terminal of a battery or other source of electrical energy 6. Sealed in the end of the tube opposite the neck 2 are relatively heavy 35 lead wires 7 and 8, the ends of which are welded or otherwise attached to the boat 9, preferably of molybdenum. Contained 40 within the boat 9 is a supply 10 of the material to be coated on the filament 5. The outer ends of the lead wires 7 and 8 are connected with the terminals of a battery or other source of electrical energy 11.

To coat a filament with this apparatus, the tube 1 is first exhausted. The coating material 10 is then heated and caused to 45 volatilize by current supplied from a battery 11. The volatilized material is deposited upon the filament 5. After a sufficient coating has been deposited upon the filament 5, current is passed therethrough

from the battery 6 in order to consolidate and harden the coating upon the filament. In this particular instance, the filament 5 is 50 a length of platinum wire and the coating material 10 is an alkaline earth oxide, such as calcium oxide, barium oxide or strontium oxide, or, a mixture of two or more of these oxides. A platinum filament provided with 55 such a coating has a greater degree of thermionic emissivity than an uncoated filament operated under the same temperature conditions.

What is claimed is:

1. In a device of the character described, a chamber, a metallic boat in said chamber for holding coating material, means for heating said coating material, and means in said chamber for supporting the filament 60 out of contact with the coating material.

2. In a device of the character described, a chamber, a metallic boat in said chamber for holding coating material, lead wires for supporting said boat and supplying electrical 70 energy thereto, and means in said chamber for supporting a filament out of contact with the coating material.

3. In a device of the character described, an evacuated chamber, a metallic boat in 75 said chamber for holding coating material, means in said chamber for passing heating current through said boat to volatilize said coating material and means for supporting a filament out of contact with the coating 80 material.

4. In a device of the character described, an evacuated chamber, a metallic boat in 85 said chamber for holding coating material, lead wires for supporting said boat and supplying electrical energy thereto, and means in said chamber for supporting a filament out of contact with the coating material.

In witness whereof, I hereunto subscribe 90 my name this 19th day of December, A. D. 1921.

ERWIN RUDOLPH STOEKLE.
